FILING DEVICE

Fred J. Kline, Bayville, N. Y., assignor to Acco Products, Inc., Long Island City, N. Y., a corporation of New York

Original application March 7, 1931, Serial No. 520,788. Divided and this application February 5, 1932. Serial No. 591,222

7 Claims. (Cl. 129—25)

This invention relates to filing devices and more particularly to an improved fastener, and holders whereby such fasteners and material secured thereby can be detachably held in suitable folders and the like. This application is a division of my co-pending application Ser. No. 520,788 filed March 7, 1931 and a continuation in part of my co-pending application Ser. No. 381,368 filed July 26, 1929.

10 Fasteners for papers, documents and similar material having prongs which pass through suitable perforations in such material and engage a compressor or locking device to securely bind the material are now in common use. When such fasteners are used to hold the material in a folder, the prongs pass through perforations in the folder or suitable holders are secured to the folder to engage and hold the fastener.

It is the object of the present invention to provide an improved fastener which is adapted to be fastened to a folder or back, and an improved holder whereby the fastener may be secured detachably to the folder or similar support.

Other objects and advantages of the invention will be apparent as it is better understood by reference to the following specification and accompanying drawings, in which

Fig. 1 is a view in perspective of the improved fastener;

30 Fig. 2 is a sectional view showing the fastener secured to a back or folder;

Fig. 3 is an elevation of a machine for securing the fasteners to supporting sheets;

Fig. 4 is a view in perspective of a portion of 35 the machine;

Fig. 5 is a sectional view of a portion of a machine;

Fig. 6 is a section on the line 6—6 of Fig. 5;

40 Fig. 7 is a view in perspective of a folder with the fastener applied thereto;

Fig. 8 is a perspective view of a holder secured to a back or folder;

Fig. 9 is a plan view illustrating the engagement of the fastener with the holder;

45 Fig. 10 is a plan view of a modified form of holder;

Fig. 11 is a plan view of another form of holder; and

50 Fig. 12 is a sectional view of the holder and fastener.

Referring to the drawings, 5 indicates the base of a fastener having prongs 6 which are adapted to pass through perforations in the papers or other material to be secured. The 55 prongs may also engage perforations 7 in a com-

pressor 8 which is adapted to rest upon the material above the fastener. When the prongs 6 are bent over the compressor, the material is securely bound. The compressor may be provided with locking means such as the slides 9 which engage the prongs after they are bent, thereby binding the material in the fastener more securely.

The base 5 is provided with two upwardly projecting spaced lugs 10 struck preferably from the metal forming the base. The lugs are preferably pointed so that they will easily pass through even relatively stiff material. One function of the lugs is to permit securing the base to any suitable material forming a back or folder. Thus, for example, if the fastener is to be mounted on a back of relatively stiff material such as card- or press-board, the prongs 6 and lugs 10 can be driven through the back by means of a suitable apparatus such as that described in my co-pending application above identified. The lugs 10 are clinched to secure the fasteners in place.

This machine (Figs. 3, 4, 5 and 6) comprises a base 11 and a pivoted arm 12 having a head 13. The head carries a pivoted guide 14 with spaced clips 15 which are resiliently held by a spring 15' adapted to receive one of the fasteners with the prongs 6 and lugs 10 depending. A die plate 16 on the base has openings 17 to receive the prongs. A pair of pins 18 on the head engage 80 openings 19 in the base 5 of the fastener and hold it in proper position until it is released. A cam plate 20 on the guide 14 engages the die plate 16 when the head descends and the guide then swings rearwardly to clear the fastener. 85

When a sheet of any suitable material 20' is placed on the die plate and the head is caused to descend, the prongs 6 and lugs 10 are forced through the material and the lugs are bent by engagement with the die plate to securely hold the 90 fastener in place. The head is then lifted and when another fastener has been inserted is ready for the succeeding operation.

The lugs 10 serve another function in connection with the holders which can be secured to a back or folder to permit detachable connection of a fastener and the material carried thereby. In Figs. 8 and 9, such a holder is shown on a back 21 to which it is secured by rivets or other fastening means. The holder comprises a plate 22 with a portion 23 thereof struck up from the body thereof. It may be of metal or any other suitable material. The portion 23 which is raised slightly above the level of the back to which 105

it is applied has oppositely disposed notches 24 and 25 and preferably a rounded corner 26.

The base 5 of the fastener is slipped under the portion 23 of the holder with one of the lugs 10 engaging the notch 25. By swinging the base of the fastener the opposite lug 10 can be brought into engagement with the notch 24 and the fastener. By moving the base in a longitudinal direction the fastener is secured until released. 10 The lugs 10 may be bent slightly to overlie the portion 23. If the fastener is secured to a back, the portion 23 is slipped between the base 5 and the back and the latter is thus secured by the holder.

15 In the device as shown in Fig. 10, the holder 26' is secured to a back 27 as in the preceding embodiment and is provided with a portion 28 raised slightly above the back. It is provided with a notch 29 and a rounded edge 30. The 20 fastener is slipped under the portion 28 with one of the lugs 10 in the notch and the other engaging the rounded edge.

25 In Fig. 11 of the drawings, the holder 31 is secured to a back 32 as in the preceding embodiments and is provided with a raised portion 33 with depressed lips 34. The base 5 of the fastener is slipped under the portion 33. The lips 34 engage the edge of the base 5 and hold it in position from which it can, however, be released readily 30 when desired.

35 The fastener and holder as described provide a simple and effective arrangement for detachably securing files of papers and the like on backs or on folders. The fastener may also be secured directly to a back or in a folder, and the apparatus described permits the application of the 40 fastener to any suitable support to which it is secured by the lugs. These lugs serve to secure the fastener permanently to the support or back and also cooperate with a holder or similar support or back or in a binder.

45 The devices as described are inexpensive and can be applied to a variety of filing equipment affording a safe and satisfactory binding means for letters, documents and other papers or material in sheet form.

50 Various changes can be made in the details of construction and arrangement of the parts without departing from the invention or sacrificing any of the advantages thereof.

I claim:

55 1. A holder for sheet fasteners comprising a base adapted to be secured to a support and an offset portion raised above the surface of the base portion at one edge thereof and having a notch 130 extending inwardly from one end adapted to engage and hold a fastener.

60 2. A holder for sheet fasteners comprising a base adapted to be secured to a support and an

offset portion raised above the surface of the base portion and having notches extending inwardly from opposite ends adapted to engage and hold a fastener.

65 3. A holder for sheet fasteners comprising a base adapted to be secured to a support and an offset portion raised above the surface of the base portion, said offset portion being split lengthwise at its ends with the outer split portion of each end being depressed to form a fastener engaging and holding lip.

70 4. A filing device comprising a holder having a base and an offset portion raised above the surface of the base and a fastener having a base, projecting prongs and lugs between the prongs, the base of said fastener being received beneath the raised offset portion of the holder and the lugs of the fastener extending into a position to engage the raised offset portion upon a shifting of the fastener to limit its movement with respect to the holder.

75 5. A filing device comprising a holder having a base and an offset portion raised above the surface of the base with a notch extending inwardly from one end, and a fastener having a base, projecting prongs and lugs between the prongs, the base of said fastener being received beneath the raised offset portion of the holder and one lug of the fastener extending into said notch and adapted, upon a shifting of the fastener, to engage the edges defining the notch to limit the movement of the fastener with respect to the holder.

80 6. A filing device comprising a holder having a base and an offset portion raised above the surface of the base with notches extending inwardly from opposite ends, and a fastener having a base, projecting prongs and lugs between the prongs, the base of said fastener being received beneath the raised offset portion of the holder and the lugs of the fastener extending into said notches and adapted, upon a shifting of the fastener, to engage the edges defining the notch to limit the movement of the fastener with respect to the holder.

85 7. A filing device comprising a holder having a base and an offset portion raised above the surface of the base, said offset portion being split lengthwise at its ends with the outer split portion of each end being depressed and a fastener having a base, projecting prongs and lugs between the prongs, the base of the fastener being received beneath the raised offset portion of the holder and the lugs in the fastener being received behind the depressed end portions of the raised offset portion whereby said depressed end portions retain the fastener in proper position with respect to said holder.

FRED J. KLINE.
